ARC PROTECTIVE MOUNTING FOR TUBE SOCKET OR THE LIKE

Herbert Fremont, Los Angeles, Calif., assignor to Calbest Engineering & Electronics Company, Los Angeles, Calif., a corporation of California

Application February 14, 1955, Serial No. 488,069

2 Claims. (Cl. 339—193)

This invention relates to an insulation mounting for electronic emission tubes, such as for high voltage television rectifier tubes, especially intended to prevent arcing between the solder pins of the tube socket and the chassis or the like.

Such mounting presents an important design problem, for the potentials encountered are of the order of 20,000 to 30,000 volts.

Provisions have been made in the past for appropriately mounting such high voltage tubes. Not uncommonly used is a pair of long polystyrene rods supporting the tube socket high above the chassis. This arrangement, although for the most part effective, consumes considerable space, and requires substantial clearance above the chassis.

Yet even this arrangement fails in installations at high altitudes, especially, when moisture conditions are adverse.

Even in the ordinary installations, failure may occur due to the fact that a pip or point incidentally produced at the soldered connections induces an arc discharge. Soldering must be skillfully and carefully done at the socket posts to avoid this cause of failure.

It is another object of this invention to overcome these disadvantages, and provide a highly effective arc protective mounting for vacuum tubes and their sockets in which skillful soldering is not critical.

It is another object of this invention to provide a highly compact arc protective mounting for a vacuum tube and its socket, thereby saving appreciable space in the apparatus.

These objects are accomplished by providing a complete enclosure for the tube socket, the enclosure being made of a material having an extremely high arcing potential.

It is another object of this invention to provide a device of this character that is simple and inexpensive, and that can easily be assembled for use in the particular installation.

This invention possesses many other advantages, and has other objects which may be made more clearly apparent from a consideration of one embodiment of the invention. For this purpose, there is shown a form in the drawings accompanying and forming part of the present specification. This form will now be described in detail, illustrating the general principles of the invention; but it is to be understood that this detailed description is not to be taken in a limiting sense, since the scope of this invention is best defined by the appended claims.

Referring to the drawings:

Figure 1 is a side elevation of an insulation mounting incorporating the present invention, shown cooperating with an electronic emission tube and in place upon a chassis;

Fig. 2 is an enlarged vertical sectional view, taken along the plane corresponding to line 2—2 of Fig. 1, the tube being removed;

2

Fig. 3 is a sectional view, taken along the plane indicated by line 3—3 of Fig. 2; and

Figs. 4 and 5 are corresponding plan views of the complementary parts of the apparatus.

5 The insulation mounting comprises a generally cylindrical cup or container member 10 open only at one end and a disc-like closure member 11 adapted to fit within the open end of the container 10. Both of these parts are made of molded plastic material having a very high 10 arcing potential, such as polystyrene, which has an arcing potential of the order of 600,000 volts per inch.

The container 10 supports therein a usual tube socket assembly 12.

This socket assembly 12 of conventional octal form, 15 is supported within the container 10 near the bottom wall 13 thereof. The socket is intended to cooperate with a high voltage rectifier tube 36.

Leads 26, 27 and 28 are soldered in place on the appropriate terminal lugs 12b of the socket assembly 12 20 prior to insertion into the container 10. Two of the leads 26 and 27 in this instance are for the filament, and the other lead 28, which is slightly larger, is for carrying the plate current. In the present instance only 25 three leads are required, the plate of the tube being connected to a terminal cap 36a.

For mounting the socket, two short integrally molded posts 15 and 16 are provided that project upwardly from the container base 13. These posts are diametrically oppositely disposed close to the inner surface of the cylindrical wall 17 of container 10.

Opposite corners of the rhombic insulation base 12a of the socket assembly 12 rest upon the ends of the posts 15 and 16, the socket lugs 12b extending toward the base 13 between the posts 15 and 16. The leads 26, 27, 30 and 28 extend upwardly about the edges of the socket 12, and out of the open end of the container 10.

Short sheet metal cap screws 22 and 23 pass through the usual apertures provided in the corners of the tube socket base 12a and threadedly engage respectively within 40 recesses 24 and 25 extending longitudinally of the posts from their upper surfaces. These screws cut their own threads within recesses 24, 25.

The disc closure 11 is placed within the container, entirely covering the socket 12, except for a circular central area including the recesses 12c for receiving the tube pins. This circular area is defined by a central aperture 35 of the closure 11. This closure 11 has shallow recesses 30 and 31 suitably located for receiving the 50 heads of the sheet metal screws 22 and 23, so that the closure 11 can rest firmly upon the tube socket insulation base 12a.

The periphery of the closure 11 corresponds in size and configuration to that of the interior surface of the cylindrical wall 17 of the container. Recesses or slots 32 and 33, extending inwardly from the peripheral edge of the closure 11, provide clearance for passage of the two filament leads 26 and 27. The recesses 32 and 33 are located symmetrically on opposite sides of the recess for one of the cap screws 22 or 23. On appropriate insertion of the closure 11, the recesses 32 and 33 are generally radially aligned with filament socket pins. A larger but similar recess 34 is provided for passage of the cathode lead 28. The leads 26, 27 and 28 fit closely in the recesses 32, 33 and 34.

65 The tube 36 may be inserted into the socket 12. The peripheral portion of the cylindrical base of the tube 36 engages about the edges of the aperture 35.

The socket 12 is essentially completely enclosed when 70 the tube 36 is in place.

The container 10 conveniently may be held in place by the aid of sheet metal cap screws 18 and 19, similar

to screws 22, 23, passing through apertures in the chassis 14 and engaging respectively downwardly opening recesses 20 and 21. These recesses 20 and 21 extend upwardly and longitudinally of the posts 15 and 16, but terminate substantially beneath the recesses 24 and 25 for the screws securing the socket 12. The sheet metal screws 18, 19, 22 and 23 are surrounded by substantial thicknesses of the polystyrene material to ensure appropriate insulation.

Other mounting means could be provided for the container 10. Thus, for instance, a flange or lugs extending laterally outwardly near the center of the container could support the container in a recess formed in the chassis 14.

The complete enclosure for the tube socket 12 completely ensures against creepage of arcs from the terminal lugs 12b. Arcing cannot occur by electrical penetration of the polystyrene material, the thickness of the plastic material being sufficient to prevent this for potentials of the order of 20,000 or 40,000 volts.

The inventor claims:

1. In a protective socket structure: a cup member made entirely of insulation material and open only at the top; a socket supported within the cup member beneath the top and in spaced relationship to the bottom of the cup member; said socket having a plurality of connector elements; there being clearance between at least a portion of the socket and the inner wall of the cup member for passage of leads from beneath the socket upwardly of the cup member; and a closure member slidably accommodated in the cup member, and having a central opening registerable with said connector elements for insertion of prongs of an electronic tube; one of said

members providing openings for upward passage in the cup of leads from beneath the socket; a tube when inserted into said socket providing with the members an enclosure for the space beneath the socket.

2. The combination as set forth in claim 1 in which the cup member has diametrically disposed integrally formed posts of insulation material extending interiorly of the cup member from the bottom thereof, the top of the posts providing surfaces upon which opposite sides of the socket may rest; the posts having recesses at said surfaces for cooperation with fastening means for the socket, said posts also having recesses at their lower ends opening exteriorly at the bottom of the cup for cooperation with fastening means for securing the cup member to a chassis or the like; the said top and bottom recesses of each post being substantially aligned, and the inner ends thereof being spaced from each other.
